UNITED STATES PATENT OFFICE

NORMAN J. URQUHART, OF DETROIT, MICHIGAN, ASSIGNOR OF TWO-THIRDS TO
HARRY W. THOMAS, OF DETROIT, MICHIGAN

SPRAYER NOZZLE

Application filed April 11, 1927. Serial No. 182,841.

The invention relates to sprayer nozzles of that type more particularly designed for use in the spraying of fine granular solids or dust and the invention consists in the novel construction as hereinafter set forth.

In the drawings;

Figure 1 is a central longitudinal section through the sprayer nozzle.

Figure 2 is a cross section on line 2—2 of Figure 1.

Figure 3 is an end elevation thereof.

Among the various uses of my improved nozzle are first the spraying of poison dust over vegetation; second, the spraying of solid dust fuels in combustion furnaces. For the latter use it is essential that the quantity of solid fuel should be very accurately proportioned to the quantity of air in the current by which it is carried. It is also necessary to change the proportion where there is variation in fuel value or weight of solid material or to suit other conditions. Where the device is used for spraying dust in the open air it is desirable to avoid as far as possible deflection or obstruction of the stream by atmospheric movement. The means for accomplishing this is also a feature of my invention.

In detail A is a T-shaped fitting which is connected by the nipple B with a swivel head C on the stationary conduit D. E is a nozzle member having a threaded engagement with and projecting forward from the fitting A, said member having at its rear end the flaring mouth F which connects with the substantially straight passage G. At the rear of the fitting A is the nozzle member H which has a screw threaded engagement with said fitting permitting of longitudinal adjustment therein. The member H has a tapered forward end I which may be adjusted into the flaring mouth F or rearward therefrom. There is also the central air jet passage J which connects with an enlarged supply passage K. This is connected by the swivel fitting L with a valve casing M having a needle or other metering valve N for regulating the quantity of air. The valve casing M is connected to an air conduit O through which the air supply is conducted thereto. There

is also a lock nut P having a threaded engagement with the member H and adapted to lock the same in different positions of adjustment.

To concentrate the projected stream and to impart thereto a greater power of penetration, the passage G through the member P is slightly twisted. This will impart a rotation to the projected current which will prevent its deflection by atmospheric disturbances. I preferably accomplish this by making the passage G of slightly oval cross section with a spiral twist from one end of the member E to the other.

With the construction as described, where the device is used in connection with a combustion furnace the dust fuel is drawn into the fitting A through the conduit D by means of the suction produced by the jet from the nozzle H. The air for producing this jet is regulated by the needle valve N in the valve fitting M and the proportionate quantity of dust fuel is obtained by adjusting the member H longitudinally toward or from the flaring mouth F of the member E. Thus the ratio between the air and the fuel may be made that best suited for complete combustion.

Where the device is used for the spraying of other dust materials such as poisons, they are drawn in and discharged in the same manner as previously described. The universal head C will permit of adjusting the nozzle so as to point in different directions and by reason of the rifling or twisting of the barrel, the stream is concentrated so as to increase its projective power and to avoid deflection of air currents.

When the nozzle member H is to be adjusted the lock nut P is first loosened and the member H then turned to screw it inward or outward, this being permitted by the swivel connection L.

What I claim as my invention is:

A dust sprayer nozzle comprising a T-shaped fitting with interiorly threaded nipples, a nozzle having a threaded engagement with one of said nipples being of substantially Venturi form with a flaring mouth in the portion engaging the fitting, said nozzle also having a rifled or twisted passage, a jet

nozzle member threaded to engage the opposite nipple of said fitting and adjustable therein toward or from said first mentioned nozzle, the forward end of said jet nozzle 5 corresponding to the taper of said flaring mouth, an air conduit connected to said jet nozzle, a metering valve for controlling air supplied to the jet nozzle and a conduit connected to the stem of the T-shaped fitting 10 through which the dust is introduced by the suction of said jet and venturi.

In testimony whereof I affix my signature.
NORMAN J. URQUHART.
